(57) CLAIM

The ornamental design for a baby teeth storage box, as shown and described.

DESCRIPTION

FIG. 1 is a perspective view of a baby teeth storage box showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view thereof, in an open configuration.

The broken lines in the drawings illustrate the portions of the baby teeth storage box, which form no part of the claimed design.
